(57) **CLAIM**

The ornamental design for a paint spray gun with surface pattern, as shown and described.

DESCRIPTION

FIG. 1 is a front and left side perspective view of a paint spray gun with surface pattern in accordance with the present design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The features shown in broken line are for illustrative purposes only and form no part of the claimed invention.
